X-RAY FILM

William Heinecke and Samuel A. Herman, New York, N. Y.; said Heinecke assignor to said Herman

Application October 10, 1947, Serial No. 779,006

10 Claims. (Cl. 250—67)

1

This invention relates to means and methods for marking photographic films, particularly dental X-ray films, so that they may be identified after development or prior thereto.

One object of the invention is to provide a film packet which does not require any careful etching or exposure to light prior to development and yet may permit of forming latent images of indicia which may be brought out during ordinary developing.

Another object is to provide a transfer material for imparting indicia to films which will not be affected by the developing acton.

To accomplish the first mentioned object we produce a latent image on a part of the film by the application of pressure to the emulsion of the film at selected areas thereon and preferably in the presence of a tribo-luminescent material and/or absorber for halogens.

For attaining the second object we may employ as a transfer medium an alcohol or oil soluble dye which is insoluble and unaffected by water and aqueous alkaline solution.

The inventive features of the invention as shown in connection with a dental X-ray film packet which briefly described includes an envelope having a cover and in which a film is folded over one end of a lead sheet to form a tag protected from the light. A marking medium layer intermediate of the cover and tag is responsive to pressure, as by a stylus or pencil, applied to the outer surface of the cover.

In the accompanying drawing showing, by way of example, one of many possible embodiments of the invention,

Fig. 1 is a plan of the packet, and

Fig. 2 is a cross-sectional view of the packet the section being taken along the line 2—2 of Fig. 1.

The packet comprises a usual photographic film 10 having a tag portion 11 folded or turned back over at least a part of the main portion of the film. A leaden sheet 12 is interposed between the main portion of the film and its tag so that exposure of the film to X-rays from below as shown in the drawing does not affect the tag. Adjacent to the exposed surface of the tag is a layer of a marking medium 14 for producing a substantially permanent marking on the developed film and described in detail hereinafter. Above the marking medium layer is disposed thereon, and preferably covering the upper face of the leaden sheet, an opaque sheet of black paper or cover 15. The paper sheet may be opaque to X-rays although it is only necessary that it be opaque to the ordinary actinic light.

A backing sheet 16 of black paper transparent

5 to X-rays and opaque to ordinary light is preferably disposed against the lower face of the film. The edge portions of the sheets and the film are secured together by a wrapper 18, described in Patent No. 2,277,364, proof against ordinary actinic light, and covering the sheets and film but preferably leaving an opening 19 at least in the region of the marking medium to lay bare the sheet 15. By means of a pointed 10 instrument such as a stylus or pencil pressure is applied through the sheet 15 to the marking medium to form indicia. If the sheet 15 is of contrasting color with respect to the pencil the indicia may appear visible on the sheet 15 as at 20.

The marking medium layer 14 may comprise a 15 binder, such as gelatin, for a tribo-luminescent material or for a halogen absorber or for water insoluble color.

20 A number of tribo-luminescent materials are known. All of these materials have the characteristic of emitting light when rubbed, scratched, cracked, struck, cleaved, or crushed. Advantage of these characteristics are taken 25 when the layer 14 of the material is subjected to pressure by a stylus on the cover 15 which transmits the pressure to the tribo-luminescent material adjacent the tag end 11 of the photographic film. Thus wherever pressure is applied to the layer 14, such as by the stylus acting through the 30 medium of the cover, a glow comparable to the indicia will be produced. This glow is more or less transient but of sufficient duration and intensity to "light strike" the tag and produce a 35 latent image on the film. The latent image remains unaffected until development for the cover 15 is still intact and no amount of ordinary light can affect the film. The layer 14 may be coated directly onto the tag 11 or on the cover 15, or 40 may be formed as a thin sheet to be disposed between the cover and tag.

The binder for the tribo-luminescent material 45 may be such as gelatin, isinglass, zein, glue, methyl cellulose, ethyl cellulose, soaps and starches.

As tribo-luminescent materials, the following may be used either singly or taken in combination.

50 Calcium salts e. g. CaS 0.003% to 0.1% of heavy metal salts;
Arsenous trioxide (As_2O_3);
Uranium nitrate ($UO_2(NO_3)_2$);
Zinc sulphide (ZnS) (containing impurities of heavy metal salts, e. g. Wurtzit);
Borates, dehydrated, in presence of organic matter;
Manganous sulphide (MnS);

Stannous chloride (SnCl_2) (without water of crystallization);

Stannic sulphide (SnS_2) plus K_2S ;

Potassium sulphate (K_2SO_4);

Sodium salts of arsenic e. g. Na_2HAsO_3 , or $\text{Na}_3\text{AsO}_4 \cdot 12\text{H}_2\text{O}$;

Saccharin;

Thiocarbamide;

Quinine di hydrochloride;

Salicylic acid or sodium salicylate;

Sodium hypophosphite ($\text{NaH}_2\text{PO}_2 \cdot \text{H}_2\text{O}$) with trace of $\text{Na}_2\text{S}_2\text{O}_3 \cdot 5\text{H}_2\text{O}$;

Phenetsal (acetyl-p-aminophenyl salicylate)
"Salophen";

Salicylidene-beta-naphthylamine;

Phthalic anhydride;

Cinchonidine sulphate (with impurities);

Acetanilide if contaminated with aniline;

Sodium or potassium bromates;

Phthalic acid (in ordinary state);

Zinc sulphide (ZnS) in combination with small quantities of ortho or meta silicic acid or of stannous salts or of titanium salts

Zinc sulphide ore "Sphalerite" (preferably from Horn Silver Mine, Utah).

Certain artificially prepared compounds exhibit triboluminescence of varying extent according to modes of preparation. For example a zinc sulfide prepared by calcining 100 g. zinc carbonate, 30 g. sulphur and 0.5 g. magnesium oxide for 30 minutes at a temperature of about 300-500° is a superior triboluminescent material when glue is used as the binder.

The action of the tribo-luminescent material may be enhanced by the addition of a reducing agent or halogen absorber, such as sodium nitrite or hydrazine salts, to the layer 14.

The entire action is not completely understood but appears to be more than a mere reduction of the halide by the reducing agent and it is probable that the light emitted during the luminescence has a greater range of activity than the simple action of the reducing agent brought into contact with emulsion at a relatively small number of points.

If the emulsion of the film is especially rich in silver halide and the layer 14 contains the reducing agent or absorber or hydrazine salts it is possible to dispense with the tribo-luminescent material. It is even possible that the reducing agent and layer 14 may be omitted but with less satisfactory results. It therefore appears that pressure alone on a rich emulsion is sufficient to produce a latent image without the need for stencils or transfer sheets heretofore employed.

It is preferable, however, to employ the reducing agent when no tribo-luminescent material is used. In such instances the binder or vehicle for the reducer may be any suitable semi-solid material inert to the reducer and emulsion such as a mixture of gelatin and glycerine or gelatin and adsorbitol. Stannous chloride may be employed both as a reducer and tribo-luminescent material.

The foregoing structures and composition depend on the reduction of the halide to produce developed indicia on an undeveloped background. Sometimes, as when positive prints are to be made, it may be desirable to develop the background and leave the indicia undeveloped. In such instances the layer 14 may be of a slightly tacky consistency, containing an oil-and-alcohol soluble light-blocking dye insoluble in water and alkalis, and the layer adhered to the cover 15.

The body of the layer may be tallow, waxes, resins (e. g. elemi) methyl abretate and suitable solvents to give the necessary tackiness such as chlorinated hydrocarbon, aromatic hydrocarbons, or alcohols. In use, the pressure of the stylus causes a transfer of the dye and its tacky vehicle from the cover to the film. The cover 15 is then removed so that light may strike the background of the indicia with the latter protected. The transferred indicia may be removed with solvent subsequent to developing if desired.

The layer 14 of marking medium is preferably made up of sphalerite and a small amount of powdered friction material or fine abrasive intimately mixed together so that when pressure is applied to the layer a particle of the sphalerite will be rubbed or scratched by the abrasive in a crunching action. The two materials may be bound together lightly by a suitable binder such as polyvinyl alcohol, zein or glue. Of course other tribo-luminescent materials may be employed in a like manner. Such a layer may be formed by dispersing the tribo-luminescent material and abrasive, such as powdered glass, in a solution of the binder and spreading the dispersion on the cover 15 and allowing the film to dry. Water may be used as the solvent for polyvinyl alcohol and glue while alcohol may be used for zein. The abrasive or friction material need not be as hard as glass or even the sphalerite itself for tribo-luminescence is obtained by merely drawing the fingernail across a crystal of the sphalerite.

The invention claimed is:

1. An X-ray film packet comprising a lead sheet; a photographic film folded over one end of the sheet and forming a tag lying on the sheet and an image receptive portion adjacent and under the sheet; a cover for the sheet and tag; a layer of tribo-luminescent material intermediate of the cover and tag, and means for holding the sheet, tag, layer and cover together.

2. A packet as in claim 1, said tribo-luminescent material being phenetsal.

3. An X-ray film packet comprising a lead sheet; a photographic film disposed below the sheet and having an end portion of the film folded up and over an end of the lead sheet and forming a tag lying on the top face of the sheet, the lower face of the portion of the film beneath the sheet being covered with a covering of material opaque to normal light and transparent to X-rays; a layer of tribo-luminescent material on the upper face of the tag; a cover opaque to normal light covering the upper face of the layer of tribo-luminescent material, and means for holding said sheet, film, covering and cover together.

4. A packet as in claim 3, said tribo-luminescent material being phenetsal.

5. In an X-ray film packet, a photographic film having one end portion folded backwardly parallel to the main portion of the film to form a tag; a leaden sheet between the tag and main portion of the sheet, the outer face of the main portion being receptive to X-rays; and a layer of tribo-luminescent material on the outer face of the tag.

6. In an X-ray film packet, a photographic film having one end portion folded backwardly parallel with the main portion of the film to form a tag; a layer of tribo-luminescent material on the outer face of the tag; a leaden sheet intermediate of the tag and said main portion whereby when the outer face of the main portion is

normally exposed to X-rays said rays will not penetrate through the sheet to the tag.

7. A photographic film device comprising a photographically sensitive sheet; a second sheet exteriorly exposed and opaque to normal natural light covering said sensitive sheet to protect the latter from ordinary light; and tribo-luminescent material intermediate of the two sheets.

8. A laminated photographic image recorder comprising a photographically sensitive sheet; a second pressure transmitting sheet exteriorly exposed and opaque to light and covering the sensitive sheet to protect same from the light; and a layer of tribo-luminescent material intermediate of the said sheets and free from opaque matter between the tribo-luminescent material and the sensitive sheet whereby pressure applied to the exposed face of the opaque sheet will be transmitted to said layer which will glow under the influence of the pressure and form an image on the sensitive sheet at points corresponding to the points of application of the pressure.

9. In an X-ray packet, a leaden sheet, a photographic film disposed below the sheet and having an end portion of the film folded up and over an end of the leaden sheet and forming a tag lying on the top face of the sheet, the lower face of film beneath the sheet being covered with a covering opaque to normal light and transparent to X-rays; a top opaque cover for the outer 30 face of tag portion and a layer of transfer ma-

terial between the top cover and the tag portion.

10. In an X-ray packet as in claim 9, said transfer material being composed of a tacky binder and an oil-soluble dye opaque to normal light, the binder being insoluble in water and in alkali.
